RECLINING ARTICLE OF FURNITURE

Anton Lorenz, Buffalo, N. Y.

Application November 2, 1945, Serial No. 626,287

4 Claims. (Cl. 155—110)

1

My invention relates to an article of furniture, and more particularly to a reclining article of furniture, wherein the back-rest and seat form movable members of a polygonal link-system swingably mounted on a support, and wherein the movements of the members of said polygonal link-system are positively controlled by a guiding link pivoted to the support and operatively connected with a member of the polygonal link-system.

An object of my invention is to provide a convenient controlling mechanism for a leg-rest swingably mounted on the seat of a reclining article of furniture of above described type, by means of which the angle between the leg-rest and the seat is automatically altered when the movable members of the reclining article of furniture including the back-rest and the seat are brought from a certain position, such as the sitting position, into another position, such as a reclined position, or vice versa.

Another object of my invention is to improve on reclining articles of furniture of above described type as now ordinarily made.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a side elevational view of an adjustable reclining chair according to the invention,

Fig. 2 is a sectional view taken on line 2—2 of Fig. 1, illustrating the locking device of the chair,

Fig. 3 is a perspective view of the support carrying the movable members of the chair shown in Fig. 1,

Fig. 4 is a perspective view of a different embodiment of a support for a chair according to the invention,

Fig. 5 is a side elevational view of a different embodiment of a chair according to the invention,

Fig. 6 is a side elevational view of a further embodiment of a chair according to the invention, wherein the effective length of some members of the chair may be adjusted,

Fig. 7 is a side elevational view of still another embodiment of a chair according to the invention,

Fig. 8 is a side elevational view of another embodiment of an adjustable reclining chair according to the invention,

2

Fig. 9 is a side elevational view of a further embodiment of a chair according to the invention,

Fig. 10 is a side elevational view of still another embodiment of a chair according to the invention,

Fig. 11 is a fragmentary side elevational view of a different embodiment of the controlling mechanism of a chair according to the invention,

Fig. 12 is a top plan view of the guiding link of the controlling mechanism shown in Fig. 11,

Fig. 13 is a sectional view taken on line 13—13 of Fig. 11, and

Fig. 14 is a fragmentary side elevational view of still another embodiment of a controlling mechanism of a chair according to the invention.

Referring now to Figs. 1 and 3, 29 generally indicates a support in the shape of a casing of any suitable material, such as metal, wood, plastic, or glass. A laterally projecting arm 22 is arranged on each side of the chair at its rear end. Each arm 22 is provided with a bore 24. Furthermore, the support 29 carries a transverse rod 26, the ends of which project on both sides of the support.

28 indicates a seat pivotally connected with a back-rest 30 by means of pivots 32. On each side of the chair, one end of a connecting link 34 hereinafter called the top connecting link is pivoted to an intermediate point of the back-rest at 35. The top connecting links 34 form the arm-rests of the chair. The other end of each top connecting link 34 is pivoted to one end of a second connecting link 36 hereinafter called the front connecting link at 38. The lower end of said front connecting link 36 is pivoted to the seat 28 at 40. Thus, the pivotally interconnected back-rest 30, the link-chain composed of the two connecting links 34, 36, and the seat 28 form the movable members of a polygonal link-system in the shape of a quadrilateral link-system. Said quadrilateral link-system is swingably mounted on the support 29 at the pivotal connection 22 between the back-rest and the seat for movement about a single axis: on each side of the chair, the pivot 22 connecting the seat 28 with the back-rest 30 is inserted into the bore 24 of an arm 22 of the support 29. On each side of the chair, the movements of the movable members of said quadrilateral link-system are controlled by a guiding link 42, the lower end of which is swingably mounted on the transverse rod 26 carried by the support, and the upper portion of which is pivoted to the link-chain or

pair of connecting links 34, 36, at the pivotal connection 38 between said connecting links.

A leg-rest 44 is pivoted to the front portion of the seat 28 at 46. Said leg-rest 44 has an extension 48 on each side of the chair, said extension projecting upwardly beyond the pivotal connection 46 between the leg-rest and the seat. The extension 48 is rigidly connected with the leg-rest 44. According to the invention, the movements of said leg-rest 44 are controlled by a controlling link 50 arranged on each side of the chair. One end of said controlling link 50 is pivoted to said extension 48 of the leg-rest 44 at 52, and the other end of said controlling link 50 is pivoted at 54 to an extension 56 rigidly connected with the main body of the guiding link 42. Said extension 56 of the guiding link projects outside the quadrilateral link-system.

The sitting position of the movable members of the chair shown in full lines is limited by the upper edge of the support, on which the seat comes to a rest.

When the occupant of the chair leans the weight of his body against the back-rest, he may readily swing the movable members of the chair into a reclined position, for example into the extreme reclined position shown in dash and dot lines in Fig. 1. As mentioned above, during such a movement the guiding link 42 controls the movements of the members 28, 30, 34, 36 of the quadrilateral link-system and the movements of the leg-rest 44 through the medium of its extension 56 and the controlling link 50.

The extreme reclined position of the movable members of the chair is limited by a stop 58 mounted on the support, which forms an abutment for the back-rest.

The movable members of the chair may be held in any desired position by means of a locking device generally indicated by 60. As best shown in Figs. 1 and 2, said locking device 60 comprises a handle 62 screwed on the threaded end of the pivot 35 between the back-rest 30 and the top connecting link or arm-rest 34. Said pivot 35 has a head 64 resting against a surface of the back-rest 30. A square portion 66 of the pivot 35 is inserted into a corresponding square aperture of the back-rest 30, whereby the pivot 35 is prevented from rotation. When the user of the chair loosens the locking handle 62, the surface of the hub 68 of said handle is disengaged from the surface of the top connecting link 34, so that the movable members of the chair may be freely moved from one position into another one. When the locking handle 62 is tightened, the surface of the hub of the handle is pressed against the top connecting link 34, whereby the latter is pressed against the back-rest 30 engaged with the head 64 of the pivot 35, so that the members of the chair are held in their position.

Of course, if desired, any other type of locking device may be used.

Fig. 4 illustrates a different embodiment of a support 20a, on which the movable elements of the chair shown in Fig. 1 may be mounted. The support 20a shown in Fig. 4 is in the shape of a casing closed at all sides.

It is understood, that the supports of the type shown in Figs. 3 and 4 may also be made of several parts connected with each other in any suitable manner.

In the embodiment of a chair shown in Fig. 5, the quadrilateral link-system 128, 130, 134, 136 swingably mounted on the support 120 at

132 and its control by the guiding link 142 substantially corresponds to similar mechanisms of the chair shown in Fig. 1. Furthermore, again one end of a controlling link 150 is pivoted at 152 to the extension 148 of the leg-rest 144 swingably mounted on the seat 128 at 146. However, the other end of said controlling link 150 is pivoted to the guiding link 142 at the pivotal connection 138 of the latter with the pair of connecting links 134, 136.

The sitting position of the movable members of the chair shown in full lines in Fig. 5 is limited by the upper edge of the support 120 on which the seat 128 comes to a rest. When the back-rest 130 is swung about its pivot 132, the movable members of the chair are brought into a reclined position, for example into the extreme reclined position shown in dash and dot lines in Fig. 5. During such a movement the guiding link 142 controls the movements of the members of the quadrilateral link-system as well as the movement of the leg-rest 144. The extreme reclined position is limited by a self-locking effect of the mechanism which is obtained as soon as the controlling link and the extension of the leg-rest come into alignment with each other in the position 150', 148' as shown in dash and dot lines.

The movable members of the chair may be held in any desired position by means of a locking device 160 of the type shown in Fig. 2.

According to Fig. 6, the quadrilateral link-system formed by the pivotally interconnected seat 228, back-rest 230, and link-chain comprising the top connecting link 234 and front connecting link 236 is swingably mounted on the support 220 at 232. On each side of the chair, the lower end of a guiding link 242 is pivoted to the support 220 at 226, and the upper end of said guiding link is pivoted to the top connecting link 234 at a point 239 spaced from the pivotal connection 238 between the top connecting link and the front connecting link. The extension 248 of the leg-rest 244 pivoted to the seat 228 at 246 is pivotally connected at 252 with one end of a controlling link 250, the other end of which is pivoted to an intermediate point of the guiding link 242 at 255. As will be readily understood, the guiding link 242 controls the movement of the members of the quadrilateral link-system 228, 230, 234, 236 and the movement of the leg-rest 244. The guiding link 242, the front connecting link 236, the extension 248 of the leg-rest, and the controlling link 250 are provided with series of holes 270, and the pivots 238, 239, 252, and 255 are disengageable so that they may be inserted into selected holes of said series of holes 270, whereby the effective length of the guiding link, front connecting link and controlling link may be varied and adjusted.

The movable members of the chair may be held in any desired position by means of a locking device 260 of the type shown in Fig. 2.

According to the embodiment shown in Fig. 7, the support 320 comprises two side frames 321 connected with each other by transverse bars 323, 326.

The rear end of the seat 328 is pivoted to the back-rest 330 at 332. The rear end of the top connecting link 334 is pivoted to an intermediate point of the back-rest 330 at 335, and the other end of said top connecting link 334 is pivoted at 341 to an intermediate connecting link 372 representing a portion of a guiding link 342 pivoted to the support at 326. The upper end of the front connecting link 336 is pivoted at 343

ly connected with the main body of the guiding link 642. One end of a controlling link 650 is pivoted to said extension 656 of the guiding link at 654, the other end of said controlling link is pivoted at 652 to the extension 648 of the leg-rest 644 pivoted to the seat at 646. Thus, said guiding link 642 also controls the movements of the leg-rest 644 through the medium of its extension 656 and the controlling link 650.

The stop 674 limits the sitting position and the stop 658 limits the extreme reclined position of the movable members of the chair.

The movable members may be held in any desired position by means of the locking device 660.

While according to Fig. 10 the extension 656 of the guiding link is rigidly connected with the main body of the guiding link 642, one end of the extension 756 of the guiding link 742 shown in Figs. 11 and 13 is pivoted to the guiding link at 776. The other end of the extension 756 is pivoted at 754 to one end of the controlling link 750, the other end of which is pivoted at 752 to the extension 748 of the leg-rest 744 swingably mounted on the seat 728 at 746. The lower end of the guiding link 742 is pivoted at 726 to the support (not shown), and the upper end of said guiding link 742 is pivoted at 737 to the front connecting link 736 pivotally connected with the seat 728 at 740. The seat 728 and the front connecting link 736 may form members of any of the polygonal link-systems disclosed in Figs. 1 and 5-10.

The extension 756 of the guiding link is provided with a longitudinal guiding slot 778. According to Figs. 11-13, the guiding link 742 is provided with a guiding slot 780 having a recess 782 in register with the lower end of the slot 756 when the extension 756 of the guiding link is in the position shown in full lines in Fig. 11. An adjusting screw generally indicated by 784 passes through both slots 778 and 780. The head 786 of the screw 784 rests against the surface of the guiding link 742, and a square portion 788 of the screw in slidable engagement with the slot 780 prevents the screw from rotation when an adjusting knob 790 is screwed on the threaded end of the adjusting screw. When the adjusting screw 784 is tightened, the extension 756 of the guiding link is held in a predetermined position relative to the main body of the guiding link 742. When the adjusting screw is loosened, the extension 756 may be freely moved relative to the main body of the guiding link 742 about its pivot 776, and, during such a movement, the adjusting screw 784 slides along the slots 778 and 780.

When the extension 756 of the guiding link is in alignment with the guiding link 742 in the position shown in full lines in Fig. 11, the extension abuts against a stop 792 secured to the guiding link 742 by suitable means, for example screws. Said stop 792 may cause a simultaneous movement of the guiding link 742 and the extension 756 of the guiding link when the guiding link is swung about its pivot 726 and the adjusting screw 784 is not tightened. Furthermore, the extension 756 and the guiding link 742 are locked in alignment with each other, when the adjusting screw 784 is displaced into the recess 782 of the slot 780 and into the end of the slot 778 registering with said recess 782.

As will be readily understood from Fig. 11, the leg-rest 744 may be brought into a different position relative to the seat 728, for example

the position 744'', by swinging the extension 756 about its pivot 776, for example into the position 756'', after a loosening of the adjusting screw 784. Now, when the adjusting screw is tightened in the position 784'', the extension of the guiding link and the guiding link are rigidly connected with each other, so that the leg-rest is held in the position 744''. Upon a movement of the guiding link 742 about its pivot 726, for example by a corresponding movement of the back-rest forming a member of the polygonal link-system including the guiding link as described above, the leg-rest is swung about its pivot 746 starting from the position 744'', until the movable members of the chair are locked, when the controlling link 750 comes into alignment with the leg-rest 744. In such a self-locking position of the movable members of the chair, the back-rest and seat have not yet reached their extreme reclined position. If it is desired to bring the back-rest and seat into their extreme reclined position, the adjusting screw 784 is loosened, whereupon the extension 756 of the guiding link abuts against the stop 792 under the weight of the leg-rest and the load acting thereon. Now, the back-rest and seat may be brought into their extreme reclined position, and, at the same time, the leg-rest is brought into its normal extreme reclined position by the guiding link 742 acting with its stop 792 on the extension 756 of the guiding link connected with the extension 748 of the leg-rest 744 through the controlling link 750.

According to Fig. 11, the extension 756 of the guiding link is pivoted to an intermediate point 776 of the guiding link 742. If desired, however, said pivotal connection between the extension 756 and the guiding link 742 may also coincide with the pivotal connection of the guiding link with a connecting link of the polygonal link-system.

According to the embodiment shown in Fig. 14, a controlling element 856 is swingably mounted on the guiding link 842 at 876. Said swingable controlling element 856 does not project outside the polygonal link-system including, for example, the top connecting link 834, the front connecting link 836, and the seat 828, and, consequently, does not form an extension of the guiding link 842. However, the functions of said swingable controlling element 856 pivoted at 854 to one end of the controlling link 850, the other end of which is pivoted at 852 to the extension 848 of the leg-rest 844, are substantially the same as the functions of the swingable extension 756 of the guiding link shown in Fig. 11. The controlling mechanism shown in Fig. 14 is also equipped with an adjusting screw 884 passing through the slot 878 of the swingable controlling elements 856 and the slot 880 of the guiding link 842. Furthermore, again an abutment 892 is secured to the guiding link 842 for engagement with the controlling element 856.

I have shown certain embodiments of polygonal link-systems controlled by a guiding link. According to the invention, the movements of the leg-rest are also controlled by said guiding link through the medium of a controlling link. It is understood, that said controlling mechanism of the leg-rest may also be applied to chairs having a polygonal link-system controlled by a guiding link wherein, however, said polygonal link-system is of a somewhat different construction.

I have described preferred embodiments of my

to said intermediate connecting link 372. The lower end of said front connecting link 336 is pivoted to the seat 328 at 340. Thus, the pivotally interconnected seat 328, the back-rest 330, the link-chain composed of the top connecting link 334, of the intermediate connecting link 372 and of the front connecting link 336 form a quinquelateral link-system, which is swingably mounted on the support 320 at 332 for movement about a single axis. The movements of 10 said quinquelateral link-system are controlled by said guiding link 342 pivoted to the support at 326 and including the intermediate connecting link 372 of the link-chain as mentioned above. It is to be understood, that, if desired, the guiding link and intermediate connecting link could be made of two separate elements which are rigidly connected with each other by suitable means, for example screws.

The leg-rest 344 swingably mounted on the 20 seat 328 at 346 has an upper extension 348 pivotally connected at 352 with one end of a controlling link 350. The other end of said controlling link 350 is pivoted to an intermediate point of the guiding link 342 at 355. When the 25 movable members of the chair are moved from one position into another one, the guiding link 342 controls the movements of the members of the quinquelateral link-system 328, 330, 334, 372, 336, and the movements of the leg-rest 344. The 30 sitting position limited by a stop 374 arranged on the support 320 is shown in full lines, and the extreme reclined position limited by a stop 358 mounted on the support 320 is shown in dash and dot lines.

The removable members of the chair may be held in any desired position by means of a locking device 360 of the type shown in Fig. 2 or of any other suitable construction.

The support 420 of the chair shown in Fig. 8 40 is made of an integral piece of tubular material bent in a suitable manner. The pivotally interconnected seat 428, the back-rest 430, the link-chain composed of the top connecting link 434, the intermediate connecting link 472 and the front connecting link 436 form a quinquelateral link-system, which is swingably mounted on the support 420 at 432 and corresponds to the quinquelateral link-system of the chair shown in Fig. 7. Furthermore, again, the intermediate connecting link 472 represents a portion of a guiding link 422 pivoted to the support 420 at 426, which controls the movements of the quinquelateral link-system.

456 indicates an element, which may be considered an extension of the guiding link 442 projecting outside the quinquelateral link-system. According to Fig. 8 the extension 456 is integral with the guiding link 442, a portion of which represents the intermediate connecting link 472, but of course the extension 456 and the guiding link 442 could be made of separate pieces of material, rigidly connected with each other in any suitable manner. One end of the controlling link 450 is pivoted to the extension 456 of the guiding link at 454, the other end of said connecting link 450 is pivoted at 452 to the extension 448 of the leg-rest 444 pivoted to the seat 428 at 446.

As will be readily understood, the guiding link 442 controls the movements of the quinquelateral link-system and of the leg-rest. The movable members of the chair may be held in any desired position by means of the locking device 460, the sitting position is limited by the stop 474, and the extreme reclined position is limited by the 70 75

stop 458, both stops being arranged on the support 420.

According to Fig. 9 the support 520 comprises two side frames 521 connected with each other by cross bars 523. The rear end of the seat 528 is pivoted to the support 520 at 531 and the lower end of the back-rest 530 is pivoted to said support at the point 533 spaced from the pivotal connection 531 between the seat and the support. The rear end of the top connecting link 534 is pivoted to an intermediate point of the back-rest 530 at 535. The other end of said top connecting link 534 is pivoted at 543 to one end of an intermediate connecting link 572. The other end of said intermediate connecting link 572 is pivoted at 543 to the upper end of the front connecting link 536, the lower end of which is pivoted to the seat 528 at 540. Thus, the movable back-rest 530, the movable link-chain composed of the three connecting links 534, 572, 536, the movable seat 528 and the stationary portion of the support 520 between the pivotal connections 531 and 533 of the seat 528 and the back-rest 530 with the support 520 form the members of a hexagonal link-system. The upper end of a guiding link 542 is rigidly connected with the intermediate connecting link 572, and the lower end of said guiding link is pivoted to the support at 526.

The extension 548 of the leg-rest 544 pivoted to the seat 528 at 546 is pivotally connected with one end of the controlling link 550 at 552. The other end of said controlling link 550 is pivotally connected to an intermediate point of the guiding link 542 at 555.

When the back-rest 530 is swung about its pivot 533, the movements of the movable members of the hexagonal link-system 528, 520, 530, 534, 572, 536 and the movement of the leg-rest 544 are controlled by the guiding link 542 so that, for example, the movable members of the chair are brought from the sitting position limited by the stop 574 into the extreme reclined position limited by the stop 558.

The movable members of the chair may be held in any desired position by means of the locking device 560.

In the embodiment shown in Fig. 10 the support 620 comprises two side frames 621 connected with each other by cross bars 623.

The rear end of the seat 628 is pivoted to the support at 631. The lower end of the back-rest 630 is pivoted to the support at the point 633 at a slight distance from the point 631. The rear end of the top connecting link 634 is pivoted to an intermediate point of the back-rest 630 at 635. The other end of said top connecting link is pivoted at 638 to the upper end of the front connecting link 636. The lower end of said front connecting link is pivoted to the seat 628 at 640. Thus, the stationary portion of the support 620 between the pivots 631, 633, the movable back-rest 630, the link-chain composed of the movable top connecting link 634 and the movable front connecting link 636, and the movable seat 628 form the members of a quinquelateral link-system. The movements of the movable members of said quinquelateral link-system are controlled by a guiding link 642, the lower end of which is pivoted to the support at 626 and the upper portion of which is pivoted to an intermediate point of the front connecting link at 637.

The upper end of said guiding link 642 has an extension 656 projecting outside the quinquelateral link-system. Said extension 656 is rigid-

invention, but it is understood, that this disclosure is for the purpose of illustration, that the invention may also be applied to various other types of articles of furniture such as garden chairs, chairs for use in railroad cars, chairs for use in airplanes, sofas, lounges, etc., and that various omissions and changes in shape, proportion and arrangement of parts, as well as the substitution of equivalent elements for those, herein shown and described, may be made without departing from the spirit and scope of the invention as set forth in the appended claims.

What I claim is:

1. An article of repose for supporting the body of a person, comprising in combination: a support, a constrained linkage having stationary link-means and a plurality of movable links, said stationary link-means being included in said support, said movable links including a seat-member, a back-rest-member, a guiding link and a chain of connecting links including a top connecting link at one end of the chain and a front connecting link at the other end of the chain, at least one of said connecting links being arranged above the plane of the seat-member, the lower end of said guiding link being pivoted to said support, the upper end of said guiding link being connected with at least one of said connecting links, said top connecting link being pivoted to an intermediate point of the back-rest-member, said front connecting link being pivoted to the front portion of said seat-member, means pivotally connecting at least one of said back-rest and seat-members with said support, a leg-rest swingably mounted on the front portion of said seat-member, and a controlling link, one end portion of said controlling link being pivoted to the body of said guiding link, the other end portion of said controlling link being pivoted to the structure of said leg-rest.

2. An article of repose for supporting the body of a person, comprising in combination: a support, a constrained linkage having stationary link-means and a plurality of movable links, said stationary link-means being included in said support, said movable links including a seat-member, a back-rest-member, a guiding link and a chain of connecting links including a top connecting link at one end of the chain and a front connecting link at the other end of the chain, at least one of said connecting links being arranged above the plane of the seat-member, the lower end of said guiding link being pivoted to said support, the upper end of said guiding link being connected with at least one of said connecting links, said top connecting link being pivoted to an intermediate point of the back-rest member, said front connecting link being pivoted to the front portion of said seat-member, means pivotally connecting at least one of said back-rest and seat-members with said support, a leg-rest swingably mounted on the front portion of said seat-member, and a controlling link, one end portion of said controlling link being pivoted to an intermediate point of the guiding link between its connections with the connecting link and the support, the other end portion of said controlling link being pivoted to the structure of said leg-rest.

3. An article of repose for supporting the body of a person, comprising in combination: a support, a constrained linkage having stationary link-means and a plurality of movable links, said stationary link-means being included in said support, said movable links including a seat-member, a back-rest-member, a guiding link and a chain of connecting links including a top connecting link at one end of the chain and a front connecting link at the other end of the chain, at least one of said connecting links being arranged above the plane of the seat-member, one end of said guiding link being pivoted to said support, the other end of said guiding link being connected with at least one of said connecting links, said top connecting link being pivoted to an intermediate point of the back-rest member, said front connecting link being pivoted to the front portion of said seat-member, means pivotally connecting at least one of said back-rest and seat-members with said support, a leg-rest swingably mounted on the front portion of said seat-member, and a controlling link, one end portion of said controlling link being pivoted to an intermediate point of the guiding link between its connections with the connecting link and the support, the other end portion of said controlling link being pivoted to the structure of said leg-rest.

4. An article of repose for supporting the body of a person, comprising in combination: a support, a constrained linkage having stationary link-means and a plurality of movable links, said stationary link means being included in said support, said movable links including a seat member, a back-rest-member, a guiding link and a chain of connecting links including a top connecting link at one end of the chain and a front connecting link at the other end of the chain, at least one of said connecting links being arranged above the plane of the seat-member, one end of said guiding link being pivoted to said support, the other end of said guiding link being connected with at least one of said connecting links, said top connecting link being pivoted to an intermediate point of the back-rest-member, said front connecting link being pivoted to the front portion of said seat-member, means pivotally connecting at least one of said back-rest and seat-members with said support, a leg-rest swingably mounted on the front portion of said seat-member, and a controlling link, one end portion of said controlling link being pivoted to the body of the guiding link, the other end portion of said controlling link being pivoted to the structure of said leg-rest.
